UNITED STATES PATENT OFFICE.

SAMUEL K. DENNIS, OF CHICAGO, ILLINOIS, ASSIGNOR TO INTERNATIONAL HARVESTER COMPANY, A CORPORATION OF NEW JERSEY.

TRENCH-GUIDE RELISTING-PLOW.

1,366,561.

Specification of Letters Patent. Patented Jan. 25, 1921.

Application filed September 18, 1919. Serial No. 324,653.

To all whom it may concern:

Be it known that I, SAMUEL K. DENNIS, a citizen of the United States, residing at Chicago, in the county of Cook and State of Illinois, have invented certain new and useful Improvements in Trench-Guide Relisting-Plows, of which the following is a full, clear, and exact specification.

The purpose of this invention is to provide a multiple plow construction intended for general soil listing work and also for cutting down the ridges of listed land by throwing the ridges to right and left into the location of the furrows between such ridges. During the last mentioned operation the supporting wheels of the plow travel in the previously formed or old furrows. The design is also intended to provide a plow structure wherein the plows may be lowered considerably more than the normal distance, in order that the wheels may travel along the tops of the ridges and permit shallow plowing or relisting between the ridges in cases, where, due to the improper growing of the crop, it becomes necessary to plow it out and replant.

The new design relates particularly to a frame structure for supporting plow carrying beams and to a mechanism for raising and lowering beams for different depths of cutting with an accompanying variation of pitch, as is necessary for overcoming vibration and properly holding the plows to their work at different depths.

The invention also relates to an arrangement of controlling mechanism for regulating the vertical pitch of the individual plows or tools with the end in view of effecting a balanced running of the machine, and by this means eliminating unsteady running or vibration which might occur when one tool has a tendency to dig more than another, or to compensate for differences in suction of the tools and to prevent the side drift of the machine.

A further purpose of the invention is to provide an improved carrying truck for resisting side motion and for properly tracking in a trench on listed ground, particularly in connection with inwardly and outwardly throwing or listing plows which are spaced

apart for the purpose of turning down a plurality of previously formed ridges.

The general arrangement by which the desired results are accomplished preferably includes the following features: A fairly rigid truck, having a longitudinal beam or reach, connecting one or more pairs of tracking wheels, and a cross beam forward which indirectly supports the forward end of the plow beams. The rear wheels of the supporting or guiding truck are placed between the plow points to effectively resist side shift of the plows. The rear end of the guiding truck is also in a sense independent of the plow frame, being free to follow irregular surfaces in the bottom of the trench or on the top of a ridge or on level surfaces, the truck structure being pivotally connected at its forward end with the plow supporting frame. The weight of the operator assists in holding the rear truck wheels down and against lateral motion, but independently of the operator's weight the draft serves to force the rear wheels to follow low surfaces due to its location with respect to the axis of the forward truck wheels, or if the front truck wheels are omitted when the device is tractor-drawn, due to its location with respect to the pivotal axis between the truck and plow frame. The rear end of the plow beams have their own supporting wheels, but are so connected that these supporting wheels not only maintain their individual plows at the proper height, but also serve the function of supporting and steadyng the gang of plows. The plow beams may be raised or lowered simultaneously at their end connections with the truck and their individual supporting wheels. In addition, each plow beam may be raised and lowered at its forward end only for the purpose of tilting the beam around its rear pivotal support to such slight extent as may be necessary for altering the relative vertical pitch of the plows.

Ordinarily, with a well constructed implement and when the separate adjusting means for the different plows are similarly set, the plows will cut at the same depth and maintain their setting, but even then, possibly due to imperceptible differences in the sur-

face curves of the plows occurring in the hardening operations, one plow may have a tendency to dig deeper than another and it becomes necessary to compensate for its action by slightly changing the vertical pitch.

One design by which the purpose of the invention may be carried into effect is shown in—

Figure 1 which is a side elevation of a plow constructed according to this invention;

Fig. 2 is a plan view of the plow shown in Fig. 1;

Fig. 3 is a detail inside elevation, illustrating the vertical pitch adjustment of the tool carrying beams;

Fig. 4 is a sectional detail of the tie bar connection between the plow beams taken on line 4—4 of Fig. 5; and

Fig. 5 is a longitudinal sectional view of one end of the tie bar and its connection with the beam wheel crank axle.

The supporting truck or main frame structure of the implement comprises a longitudinal reach beam 1, and a transverse beam 2 near its forward end. A pair of truck wheels 3 are shown at each end of beam 1, the wheels of each pair being suitably spaced apart for running in a single trench while being guided by ridges on each side of the trench. A bent axle 4 for the rear truck wheels is rigidly clamped to the reach bar 1, while an axle 5 for the front truck wheels is carried by vertical shaft 6 which is journaled in arms 7 bolted to the forward end of reach bar 1. Shaft 6 being rotatably mounted, permits steering by the front truck wheels, this shaft carrying a clevis bar 8 for attachment to draft appliances not shown.

For the purpose of supporting the plow beams 9 in the desired manner on the main frame, a secondary or plow beam supporting frame is carried by the beam 2 and the wheels 10. This secondary frame may consist of a

crank shaft 11, the tie bar 12 and the connection between the crank shaft 11 and the tie bar provided by the plow beams 9. The bearings 13 of the crank shaft are securely fastened to cross beam 2. Rotation of the crank shaft results in crank portions 14 moving around the bearing axis of the shaft, and therefore raising or lowering the front ends of the beams 9 and through link connections 15 between the forged crank ends 16 of shaft

11 and the crank axles 17 for wheels 10, rear ends of the beams 9 are raised or lowered. The links 15 are pivotally connected at their rear ends to arms 18, in turn clamped to the longitudinal portions 19 of crank axles 17.

The laterally extending wheel supporting portions of the crank axles 17 carry rotatable sleeves 20, to which wheels 10 are adjustably keyed. The upper inwardly extending portions 21 of the crank axles 17 extend into the ends of the hollow tie bar

12 and are prevented from shifting lengthwise of the tie bar by the collar arrangement shown in Fig. 5 consisting of a collar 22 secured to part 21 of the crank axle, and a collar 23 secured to the tie bar 12 and having an extension 24 provided with an inwardly formed flange 25 for partially encircling the end of collar 22 and holding the collar 22 and crank axle in place. In order to remove one of the crank axles, the set screw 75 of the corresponding collar 23 is loosened. The crank axle may then be drawn out of tie bar 12, carrying collar 23 with it.

The connections previously mentioned between the crank portions 14 of crank shaft 80 11 and the tool supporting beams comprise brackets 26 having a plurality of horizontally and laterally spaced apertures 27 at which points bell crank levers 28 are adjustably secured. The tool beams 9 are pivotally connected to the bell crank levers 28 at the elbows of the levers by the bearing members 29. The upwardly extending arms 30 of bell crank levers 28 are secured at two points to vertical pitch regulating levers 31. Levers 31 are normally retained in their set positions against relative motion with respect to the tool beams 9 by notched quadrants 32 engaged by locking pawls 33 carried by the levers 31. The quadrants 32 are pivotally connected for limited motion with respect to the tool beams 9, but such pivotal motion of the quadrants is normally prevented by their connections with the levers 31.

When one of the vertical pitch regulating levers 31 is released from its quadrant 32 and is rocked around its bearing 29 with beam 9, considering the lever 31 and its bell crank lever 28 as a single element, the bearing 29 is slightly raised or lowered, swinging with it the bracket member 26 around the axis of the crank portion 14 of crank shaft 11. This results in a slight vertical motion of the beam around its point of support at its rear end. The relative angular setting of the lever 31, beam 9 and quadrant 32, being changed by the adjustment, the adjustment may be maintained by permitting locking pawl 33 to enter the opposed interdental of the quadrant.

An adjustment of a single lever 31 is rarely required, since it causes a change in pitch of its corresponding plow with respect to the remaining plows.

A like adjustment of both levers 31 may be utilized for different purposes, and in this case the pitch of all plows would be uniformly changed as becomes desirable at times, due to differences in weight or other conditions of the soil affecting the action of the plows in holding to their work.

Both levers 31 are also adjusted uniformly in a rearward direction to uniformly increase the vertical pitch of all plows when the implement is used for relisting. In the latter

case, the plows may be lowered the maximum or nearly the maximum extent as the supporting wheels 3 and 10 travel along the tops of the ridges when the plows are in the bottoms of the furrows, but at this time are normally employed for shallow cutting only.

The reason for materially increasing the vertical pitch of all plows when relisting is that in the normal raising and lowering of all plow beams for depth regulation by means of a lever 34, the vertical pitch of the plows is decreased according to an increase in depth. When the plows are cutting shallow, their pitch must be increased over what it is for the normal depth of cutting, in order to offset the tendency of the plows to steer upwardly out of the ground. Accordingly, when the plows are lowered to near the maximum extent the pitch is slight, and therefore to make the implement suitable for relisting purposes it is necessary to provide a separate vertical pitch adjustment for the plows with respect to their normal pitch when in the lowered positions.

The depth regulating lever 34 is journaled at 35 to a bracket secured to the side of the reach beam 1, and at its lower end is connected by a link 36 with an arm 37 rigidly secured to crank axle 11. The depth regulating lever is secured in its set position by a spring locking pawl in coöperation with the notched quadrant 38 fastened at its ends to one side of the reach bar 1 adjacent lever 34. The links 15 connecting the arms 16 of the crank shaft 11 with the crank axles 17 serve to transmit the rotary motion of crank shaft 11, effected by the lever 34 to the crank axles. If lever 34 is adjusted forwardly, the crank portions 14 of shaft 11 will lower from the position indicated by full lines in Fig. 1, and the crank axles 17 will rock upwardly around their journals in the ends of tie bar 12. The crank portions of the crank shaft 11 and the crank axles 17 are of different lengths, or may have different angular settings, for the purpose of insuring the desired uniform variation in pitch of the tools or plows, as required for cutting at different depths.

Counterbalancing spring 39 for the plow beams is attached at one end to a rearward extension of link 36, and at the other end is hooked to an eye extending rearwardly from transverse frame beam 2.

The tie bar 12 connecting the rear ends of the plow beams is securely fastened to the beams by U-bolts 40 passing around the lower sides of the tie bars and through apertures in bracket members 41 securely fastened to plow beams 9.

The maximum pitch adjustment under the action of levers 31 when both of these levers are moved rearwardly as far as pos-

sible is illustrated in Fig. 3. The bearing 29 moves through an arc, the center of which is in a horizontal plane with the crank portion 14 or crank shaft 11. Accordingly, there is but an extremely slight longitudinal motion of the beams 9 upon such adjustment, and practically none when only one of the levers 31 is adjusted for the purpose of compensating for some permanent difference in digging action of the different plows. When both levers 31 are adjusted, the plow beams pivot on portions 21 of crank axles 17. Likewise when the depth regulating lever 34 is adjusted, the plow beams pivot at the same point, but the crank axles 17 are also rocked around the same center. When only one lever 31 is adjusted to the limited extent required for compensating for some normal difference in pitch a torsional action takes place in the tie bar 12. Beams 9 being preferably securely fastened to the tie bar, the latter resists angular motion of a plow beam around the tie bar when another plow beam is locked against motion. The result of this resistance is that instead of torsioning the tie bar 12 other than may be easily accomplished, due to its elasticity, the forward end of the adjusted plow beam tends to push upwardly or downwardly on the cross frame member 2 according to the direction of the adjustment. The main frame is in fact slightly tilted by the action, not away from the true horizontal plane, but toward such position, for the reason that the unequal action of the plows which necessitated the adjustment, results in a lateral tilting of the main frame. This tilting indicates the faulty action to the operator who then adjusts one of the levers 31 until the frame is brought back to a true horizontal position. Incidentally, the relative pitch of the plows is changed to that required to cause the machine to run level.

When the plows are in a raised position, as indicated in Fig. 1, the axis of the wheels 10 comes in substantially the same vertical plane as the axis of the rear truck wheels 3, as desired for permitting the easy turning of the vehicle when the plows are out of action. When the plows are in action, the two sets of supporting wheels are relatively positioned to resist forces tending to divert the implement from its true course.

In plowing operations, the depth of cut is regulated by an adjustment of lever 34, normally no adjustments of the levers 31 being required, but when the implement is used for relisting purposes, levers 31 are moved rearwardly in order to restore the pitch necessary for shallow plowing. In the latter operation, it is necessary to lower the plows below the bottoms of the supporting wheels an abnormal distance, and the operation of lever 34 in a direction necessary for lowering the plows results in a de-

crease in pitch which must be compensated for.

While there is shown and described but one embodiment of the invention, it is to be understood that it is capable of modifications which do not depart from the scope of the invention, as disclosed in the appended claims.

1. An agricultural implement, comprising a supporting frame and wheels journaled thereon, a plow beam supported for vertical adjustment at one point on said frame, a ground wheel having a vertically adjustable connection with said plow beam for supporting the beam at another point, connected means for simultaneously adjusting the beam with respect to the frame and beam supporting wheel, and means for independently adjusting the beam relatively to said ground wheel.
2. An agricultural implement, comprising a central longitudinal frame supported by wheels longitudinally spaced for tracking in a furrow, a transverse frame member, a pair of plow beams having vertically adjustable pivotal connections with said transverse frame member, a supporting wheel for each beam connected therewith, to permit relative vertical adjustment of the beams, and connected means for simultaneously and vertically shifting both plow beams at their pivotal connections with said transverse frame member and at their connection with the beam supporting wheels.
3. An agricultural implement comprising a central longitudinal frame supported by wheels longitudinally spaced for tracking in a furrow, a transverse frame member, a pair of plow beams having vertically adjustable pivotal connections with said transverse frame member, a supporting wheel for each beam connected therewith, to permit relative vertical adjustment of the beams, connected means for simultaneously and vertically shifting both plow beams at their pivotal connections with said transverse frame member and at their connections with the beam supporting wheels, and separate means for vertically shifting each plow beam with respect to its supporting wheel.
4. In an agricultural implement, a supporting truck, a plow beam, a toggle connection between the forward end of said beam and the truck, an independent support to which the beam is pivotally connected at

another point, means for straightening or breaking said toggle for the purpose of adjusting said beam around said independent support, and means for bodily moving said toggle connection vertically and simultaneously, vertically adjusting the beam at its connection with said independent support.

5. An agricultural implement comprising a supporting truck and a plow frame pivotally connected at their forward ends, said truck having forward and rearward supporting wheels and said plow frame having independent supporting wheels substantially in lateral alinement with the rear truck wheels.

6. An agricultural implement comprising a supporting truck and a plow frame pivotally connected at their forward ends, said truck having supporting wheels and said plow frame having independent supporting wheels substantially in lateral alinement with the truck wheels.

7. An agricultural implement comprising a truck having a supporting wheel mounted thereon, a plow connected to said truck, said plow being provided with a separate supporting wheel, and means for longitudinally shifting said supporting wheel into and out of alinement with the truck wheel.

8. An agricultural implement comprising a truck having a supporting wheel mounted thereon, a plow connected to said truck, said plow being provided with a separate supporting wheel, and means for longitudinally shifting said supporting wheel into and out of alinement with the truck wheel and simultaneously raising or lowering the plow with respect to its supporting wheel.

9. An agricultural implement comprising a truck, and a supporting wheel therefor, a plow connected to said truck, a crank axle journaled on said plow, a separate supporting wheel journaled on said crank axle, means for adjusting the crank axle around its pivotal support on the plow, said crank axle being mounted on the plow in suitable position to bring its supporting wheel in lateral alinement with the supporting wheel of the truck when the plow is raised and to move the plow supporting wheel out of alinement with the truck wheel when the plow is lowered.

In testimony whereof I affix my signature.

SAMUEL K. DENNIS.
